UNITED STATES PATENT OFFICE.

JOHN YOUNG, OF CHILLICOTHE, OHIO.

PRESS.

1,267,492.

Specification of Letters Patent. Patented May 28, 1918.

Application filed November 8, 1916. Serial No. 130,256.

To all whom it may concern:

Be it known that I, JOHN YOUNG, a citizen of the United States, residing at Chillicothe, in the county of Ross and State of Ohio, 5 have invented certain new and useful Improvements in Presses, of which the following is a specification.

This invention relates to presses, particularly baling presses, although the invention 10 is not specifically limited to the same. Primarily, my invention relates to means whereby a press of this type may be readily transported from place to place by mechanism carried by itself. It is oftentimes desirable 15 to move a press from one location to another and inasmuch as these presses are usually of considerable weight, it has been a source of considerable inconvenience to place them upon a truck or otherwise transport them.

20 Another object of my invention resides in means for operating the roller supporting structure to transfer the weight of the press from the main framework to the rollers by the operation of the plunger operating 25 means of the press itself. This arrangement does away with additional mechanism used solely for the purpose of transferring the weight of the press from the main framework to the rollers.

30 Still a further object of my invention resides in a structure for transferring the weight of the press from its main framework to the roller structure, which may be operated either while moving the plunger 35 up and down or by leaving the plunger stationary, but at the same time utilizing the plunger operating means for accomplishing this end. This arrangement may be had by the provision of a peculiar type of clutch 40 or other connecting mechanism between the plunger and its operating means as will be described.

The preferred embodiment of my invention is shown in the accompanying sheets of 45 drawings, in which similar characters of reference designate corresponding parts, and in which:

Figure 1 is a central vertical section taken through a press and showing my invention 50 applied thereto,

Fig. 2 is a horizontal section taken on line 2-2 of Fig. 1,

Fig. 3 is a vertical section taken on line 3-3 of Fig. 1,

Fig. 4 is a view in perspective of a gear 55 wheel forming a portion of the operating mechanism as used by me, and,

Fig. 5 is a fragmentary view in perspective showing the roller structure and a portion of its operating mechanism. 60

In these drawings, I have not attempted to show the completed press structure, but have confined myself to the showing of a general frame work which comprises up-standing end channels 1, transverse upper 65 channels 2 and transverse lower channel members 3. End base members 4 are provided in order to give stability to the structure when it is resting upon the press framework and also, the base channels 2 have been 70 provided with a bottom plate 5 between which and the plunger plate 6, the material operated upon is adapted to be compressed. This plunger plate is connected to a pair of rack members 7 designed to mesh with pinions 8 carried upon the shaft 9, which shaft is suitably journaled as is shown at 10 at its opposite ends in the main framework. 75

This shaft 9 forms a portion of the plunger operating means and its projecting end 11 80 is provided with an internally and externally toothed gear 12. This gear is rotatably mounted upon the shaft, but is keyed thereto by means of the hand wheel 13, which latter is itself slidably keyed to the shaft 9, 85 as is shown, and whose hub 14 is provided with a series of teeth 15 to mesh with the internal teeth of the gear 12. Thus, when the hand wheel 13 is in the position shown in full lines in Fig. 1, the gear 12 is operatively keyed to the shaft 9, but when this hand wheel is in the position shown in dotted outline in Fig. 1, this gear is rotatably mounted on the shaft 9. The gear 12 also 90 meshes with a pinion 12^a, which rigidly carries a worm wheel 16 to one side, the combined spur and worm gear being rotatably mounted on the stub shaft shown at 17. A worm 18 mounted on the shaft 19 meshes with a worm wheel 16, as is shown and this worm is rigidly keyed to the shaft 19 so that 95 operation of the hand wheel 20 causes the entire train of gearing to be set in operation. Thus, by rotating the hand wheel 20, the worm 18 is rotated to correspondingly rotate the worm wheel 16 and spur pinion 12^a. 100

This latter meshes with the spur gear 12 and, when the hand wheel 13 is in the position

shown in full lines in Fig. 1, the shaft 9 is also rotated to correspondingly move the plunger 6.

When the press is in use, its framework 5 rests directly upon the floor, but when it is desired to transport the same, the rollers shown at 21 are moved to the position shown in dotted outline in Fig. 1, whereby the entire press will be supported upon them 10 and may thereby be readily transported. These rollers are mounted on shafts 22, which latter are suitably supported in a yoke member, designated by the reference numeral 23. This yoke member is pivotally mounted at 15 its two ends, as is shown at 24, to the main framework, but its opposite end is operatively connected, as is shown at 25, to a strut member 26. The upper end of this strut is slidably mounted in a casting shown 20 at 27, which casting forms a portion of one of the bearings 10 and also a portion of the means for supporting the stub shaft 17. To the upper end of the strut 26 there is pivotally attached at 28 a catch member of the 25 nature shown at 29. This catch member comprises a body portion with an upstanding lug 30 at one end, which forms the means of pivotal connection with the strut and its other end is provided with a shoe projection 31, the entire catch member resting upon the 30 horizontal leg 32 of the shelf member shown at 33 when it is in the position shown in Figs. 1 and 3. Referring to Fig. 4 particularly, it will be noted that the gear wheel 12 is provided with a plurality of laterally projecting pins 34, which pins are arranged to coöperate with the shoe projection 31. Thus, when the catch member 29 is moved from the 35 position shown in full lines in Fig. 3, to the position shown in dotted lines in this figure, the shoe projection 31 will lie in the path of rotative movement of the pins 34. As soon as one of these pins engage the shoe, the strut 26 will be forced downwardly to correspondingly move the right hand end of 40 the yoke member 23. Sufficient movement of this yoke member will bring the rollers 21 into engagement with the floor and in this manner the weight of the entire press is 45 transferred from the framework to the 50 rollers.

These rollers 21 may be moved to their supporting position simultaneously with the movement of the plunger 6, by leaving the hand wheel 13 in the position shown in full lines in Fig. 1, or this hand wheel may be withdrawn to assume the position shown in dotted lines in Fig. 1 and by operating the hand wheel 20, the plunger 6 will remain in 55 its position, while the rollers 21 are being moved to a position of support for the entire structure. No matter whether the plunger is being moved or not, the drive connection between the worm wheel 16 and the

worm 18 causes a lock to prevent the rollers 65 from returning to a position of non-support.

From the foregoing description, it will be apparent that I have provided a type of press which, under normal conditions, has a support upon the floor by means of its 70 framework. However, should it be desired to transport the same, the rollers 21 may be readily moved to a supporting position to effect such transportation.

What I claim, is:

1. In a press, a frame structure, a roller structure capable of supporting said frame structure when in an active position but to allow the frame structure to rest on a base when the roller structure occupies an inactive position, a vertically movable plunger, mechanism for effecting the vertical movements of said plunger, and a strut member coöoperative with the plunger moving mechanism and the roller structure for moving 80 the latter from an inactive position of non-support of said frame structure to an active one of supporting the latter.

2. In a press, a frame structure, a roller structure capable of supporting said frame 90 structure when in one position but allowing said frame structure to rest on the floor when in the other position, a plunger movable up and down, means for moving said plunger up and down, means whereby said 95 plunger operating means may be disconnected from operative connection with said plunger, and means operated by said plunger operating means for moving said roller structure from a position of non-support of said frame structure to one of supporting it, said last specified means being operable whether said plunger operating means are operatively connected with said plunger or not.

3. In a press, a frame structure, a roller structure capable of supporting said frame structure when in one position but allowing said frame structure to rest on the floor when in the other position, a plunger movable up and down, means for moving said plunger up and down, means whereby said plunger operating means may be disconnected from operative connection with said plunger, and means operated by said plunger operating means for moving said roller structure from a position of non-support of said frame structure to one of supporting it, said last specified means being operable when said plunger operating means is operatively disconnected from the plunger.

4. In a press, a frame structure, a roller structure capable of supporting said frame when in one position but allowing the frame structure to rest on the base when in its other 12 position, said roller structure comprising a yoke member pivoted to the frame structure at one end, rollers carried by said yoke in-

- termEDIATE of its ends, a vertically movable plunger, mechanism for effecting the vertical movements of said plunger, said mechanism including a gear carried by the drive shaft thereof, studs projecting from one side of said gear, a connecting structure operable to shift said roller structure from inactive to active positions and vice versa, and a clutch member pivotally carried by said connecting structure and capable of engaging with the studs of said gear to effect the movements of said roller structure.
5. In a press, a frame structure, a roller structure capable of supporting said frame when in one position but allowing the frame structure to rest on a base when in its other position, said roller structure comprising a yoke member pivoted at one end to the frame structure, rollers carried by said yoke member, a vertically movable plunger associated with said frame, operating means for said plunger including a drive shaft, a worm locked gear carried by said shaft, studs projecting from said gear, a roller structure shifting mechanism embodying a vertically movable strut, and a pivoted catch member carried by the upper end of said strut and movable into engagement with the studs of said gear, whereby said roller structure may be positioned to support the frame structure.
- 10 30
6. In a press, a frame structure, a roller structure capable of supporting said frame when in one position but allowing the frame structure to rest on the floor when in the other position, said roller structure comprising a yoke member pivoted to the frame at one end, rollers carried by said yoke intermediate its ends, a plunger movable up and down, a strut member attached at one end to the free end of said yoke, and a catch member pivotally carried by the other end of said strut member and arranged to be thrown in mesh with said plunger operating means to force the free end of said yoke member down to support said frame structure upon said rollers.
